SIGHTING DEVICE FOR GUNS

James C. Karnes, Buffalo, N. Y.

Application October 9, 1934, Serial No. 747,555

4 Claims. (Cl. 33—49)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a sighting device for guns and is an improvement on the device shown in my Patent No. 1,859,564 of May 24, 1932.

Field artillery gun carriages are subjected to severe usage and in travelling over rough ground 10 at high speed they frequently overturn. Under these circumstances the sight mount, which heretofore has been the highest part of the carriage, is usually damaged or destroyed.

The purpose of the invention is to arrange the 15 sighting device so that, by a slight modification, the angle of site mechanism may be utilized to lower the sighting device to a protected position.

A further object of the invention is to mount the support shaft of the sighting device without 20 having it pass through the trunnion of the gun cradle.

With the foregoing and other objects in view, the invention resides in the novel arrangement and combination of parts and in the details of 25 construction hereinafter described and claimed, it being understood that changes in the precise embodiment of the invention herein disclosed may be made within the scope of what is claimed without departing from the spirit of the invention.

30 A practical embodiment of the invention is illustrated in the accompanying drawings, wherein:

Fig. 1 is a view in side elevation of the sighting device showing it in the operative position;

Fig. 2 is a similar view showing the sighting 35 device in the lowered or protected position;

Fig. 3 is a view in rear elevation;

Fig. 4 is a sectional view on the line 4—4 of Fig. 1; and

Fig. 5 is a sectional view on the line 5—5 of 40 Fig. 4.

There is shown at A the side plate of a gun carriage which is adapted to be rotated on a suitable base for the purpose of training the gun. A cradle B which is adapted to reciprocally carry 45 the usual gun barrel C is mounted on the carriage by means of trunnions D—D.

Referring to Figs. 1, 2 and 3, a bracket 5 attached to the left side plate of the gun carriage A by means of bolts 6 has a laterally offset portion 7 whose upper end is formed into a bearing 8 positioned parallel with and preferably co-axially with the trunnions. An anti-friction bearing unit 9 within the bearing 8 carries an independently 50 rotatable support shaft 10 which has a positioning

member 11 on its inner end adapted to enter a recess 12 in the left trunnion D of the cradle.

The support shaft 10 is associated with a sight and sight mount similar to the disclosure in my patent previously referred to. Briefly, it carries a pin 13 which constitutes the axis of cross-level and is parallel to the axis of bore of the gun. Mounted on the pin is an annular bearing member 14 embraced by an annular sight mount 15 that is rotatable with respect to the bearing member. 10 The upper portion of the sight mount is formed with a socket 16 for receiving an adapter 17 which supports a telescopic sighting instrument 18.

The lower portion of the sight mount pivotally carries a worm wheel sector 19 mounted to slide 15 in a block 20 secured to an arm 21^a of a rocker 21 journaled on the bearing 8. The block 20 also carries a shaft 22 having a worm 22^a in mesh with the sector 19 and serving to move the sight mount about the axis of cross-level 13.

Referring to Figs. 4 and 5 the rocker 21 is formed with an arcuate rack 23 meshing with a worm 24 on an operating shaft 25 carried by the offset portion 7 of the bracket 5. A minor portion of the movement provided by this arrangement is for the purpose of shifting the sight mount as an entity through a longitudinal angle to compensate for subsidence of the carriage or lack of fore-and-aft level. A spirit level 26 carried by the sight mount indicates when the sight 30 mount is levelled longitudinally.

The major portion of the movement provided by the rack 23 and operating shaft 25 is for the purpose of lowering the sighting mechanism to a substantially horizontal position (Fig. 2) when 35 not in use and thereby reducing its liability to damage, especially during travel. When the gun is brought into action the sighting mechanism is quickly and easily moved into operative position.

I claim:

1. In combination, a gun carriage, a cradle having trunnions in the carriage, a bracket secured to the carriage and including a bearing, a support shaft journaled in the bearing coaxial with one of the trunnions and having a positioning member engaging said one of the trunnions, a sight mounting carried by the support shaft, a rocker journaled on the said bearing of the bracket and associated with the sight mounting, a segmental rack on the rocker, and operating 45 mechanism carried by the bracket for angularly displacing the rack and sight mounting, said rack being of sufficient angular extent to permit displacement of the sight mounting between a horizontal and a vertical position.

50

55

2. In combination, a gun carriage, a cradle having trunnions in the carriage, a bracket secured to the carriage and including a bearing, a support shaft journaled in the bearing, a sight 5 mounting carried by the support shaft, a rocker journaled on the said bearing of the bracket and associated with the sight mounting, a segmental rack on the rocker, and operating mechanism carried by the bracket for angularly displacing the rack.
10 the rack and sight mounting, said rack being of sufficient angular extent to permit displacement of the sight mounting between a horizontal and a vertical position.
3. In combination, a gun carriage, a cradle 15 having trunnions in the carriage, a bracket secured to the carriage and including a bearing,

a support shaft journaled in the bearing, a sight mounting carried by the support shaft, a rocker journaled on the said bearing of the bracket and connected with the sight mounting, a segmental rack on the rocker, and operating mechanism 5 carried by the bracket for angularly displacing the rack.

4. In combination, a gun carriage, a cradle having trunnions in the carriage, a bracket secured to the carriage and including a bearing 10 coaxial with one of the trunnions, a support shaft journaled in the bearing and having a positioning member engaging said one of the trunnions, and a sighting device carried by the support shaft.

15

JAMES C. KARNES.
